US0D1096649S

(12) **United States Design Patent** (10) **Patent No.:** **US D1,096,649 S**
(45) **Date of Patent:** **** Oct. 7, 2025**

(54) **ELECTRICAL OUTLET EXTENDER**

(71) Applicant: **Zhewen Song**, Xiangcheng (CN)

(72) Inventor: **Zhewen Song**, Xiangcheng (CN)

(**) Term: **15 Years**

(21) Appl. No.: **29/996,788**

(22) Filed: **Apr. 2, 2025**

(51) **LOC (15) Cl.** **13-03**

(52) **U.S. Cl.**

USPC **D13/137.2**

(57) **CLAIM**

The ornamental design for an electrical outlet extender, as shown and described.

DESCRIPTION

FIG. 1 is a front, top and right-side perspective view of an electrical outlet extender showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear, bottom and left-side perspective view thereof.

The broken lines throughout the drawing figures depict portions of the electrical outlet extender that form no part of the claimed design.

1 Claim, 8 Drawing Sheets
